UNITED STATES PATENT OFFICE.

JOHN SCHOEN, OF CHICAGO, ILLINOIS.

IMPROVEMENT IN SOFA-BEDSTEADS.

Specification forming part of Letters Patent No. **170,403**, dated November 23, 1875; application filed October 8, 1875.

To all whom it may concern:

Be it known that I, JOHN SCHOEN, of Chicago, in the county of Cook and State of Illinois, have invented an Improved Bed-Lounge, of which the following is a specification:

My invention relates to an improvement in folding or bed lounges, and has for its object to provide a simple means for securing the head-rest in position when the lounge is arranged as a bed.

The invention consists in the construction of and the manner of securing the head-rest frame to a slotted plate at each side of the bed when extended.

Figure 1 is a perspective view, showing the lounge opened out to form a bed, with the head-rest in position. Fig. 2 is a detail perspective view of the head-rest, showing the manner of its attachment to the bed. Fig. 3 is a longitudinal section of the same.

In the drawing, A represents a lounge-bed opened out to form a bed, at the foot of which, at each side thereof, there is secured a metal plate, B, having a slot, a, and, nearer the foot, a rib, b. C is an iron frame, bent to a U shape and upholstered, except at the extremities, to form a head-rest, which is secured in position by inserting the ends in the slots a,

the ends being scarfed to hook under the ends of the slots. A notch, c, is cut in the under edge of the frame, at each side, to drop over the rib b and lock the head-rest firmly in position.

The principal advantages of my device are its simplicity of construction and the firmness with which the head-rest frame is held in position.

I am aware of Patent No. 156,131, granted to H. S. Carter, October 20, 1874, and hereby disclaim the same as making any part of my invention. I am also aware that devices of the same general character as those described above have been used, and I do not, therefore, claim any of them, broadly; but

What I claim as my invention is—

The notched rest-frame C, provided with notch c upon the under side, in combination with the plates B, provided with slots a, to engage with the scarfed ends of the frame, and the upwardly-projecting ribs b, to engage with the notches c, for the purpose specified.

JOHN SCHOEN.
